UNITED STATES PATENT OFFICE.

WILLIAM WIRT BROWN, OF WATERVILLE, MAINE.

COAL-SCREEN.

SPECIFICATION forming part of Letters Patent No. 657,508, dated September 11, 1900.

Application filed February 23, 1900. Serial No. 6,320. (No model.)

To all whom it may concern:

Be it known that I, WILLIAM WIRT BROWN, a citizen of the United States, residing at Waterville, county of Kennebec, State of Maine, 5 have invented a new and useful Coal-Screen, of which the following is a specification.

My invention relates to devices for sifting or screening coal from ashes and the like; and its object is to prevent the raising or escape of dust and fine ashes during said process, which is ordinarily very annoying to the operator.

In the accompanying drawings, Figure 1 represents a perspective view of the screen-frame. Fig. 2 represents a perspective view of the sliding plate and cover. Fig. 3 represents a longitudinal section of said parts combined and ready for operation, and Fig. 4 represents a cross-section on line xx of Fig. 3.

20 A designates the screen-frame, which is made of shovel or scoop form and consists of two vertical parallel side plates A', a vertical back plate B, connecting said side plates at their rear ends, a horizontal strip or plate E, connecting the front ends of the side plates at the bottom and forming the lip of the screen-frame, a series of parallel wires D, forming the screen-bottom, which extend from said lip to the bottom of the back plate B, and a handle C, attached to the center of said back plate and projecting rearwardly therefrom. The front edges a of the side plates A' slant back and up from the lip or connecting - strip E to the upper edges a' , which are horizontal, so that said upper edges are about two-thirds as long as the corresponding lower edges. The plates A', B, and E are preferably made of thin sheet-iron.

25 G designates a flat sliding plate, preferably of thin metal, on which the screen is to be placed when in operation. This plate has a central rectangular opening H of area equal to the inner area of the screen-bottom, said opening being surrounded at its sides and back by a raised rim or vertical flange I, parallel to the edges of said opening and far enough removed therefrom to leave a ledge h, upon which the bottom edges of the side and back plates of the screen-frame may rest, 45 said rim I fitting closely about the outside of the lower edges of said plates when the screen-frame is in position, as shown in Fig.

3. At the front edge of said opening H is hinged a cover F, made in two sections F' and F², which are also hinged together and provided with downward flanges J at their free edges. These sections are so shaped and arranged that when the screen-frame A is placed in position the section F' will rest on the inclined front edges a of the screen-frame and the section F² on the horizontal top edges a' , thus entirely covering the said screen-frame. The flanges J are adapted to fit closely around the edges a and a' and the upper edge of the back plate B, thus preventing the escape of dust or ashes. A funnel-shaped hopper H' is attached to the said sliding plate beneath the said opening H and tapers downward and inward therefrom to diminish the spreading of the dust or ashes 70 and guide the same in its descent after passing through the screen.

K designates an ash box or receptacle to receive the dust or ashes passing through the screen and opening H in the plate G, which is placed over said receptacle when in operation. This box K has an opening K' in its top of width equal to the opening H and of such length that when the sliding plate is placed over it and reciprocated the hopper 80 H', which projects down into the ash-box, will by striking against the edge of the opening K' prevent the sliding plate from uncovering any portion of the said opening at any point of its movement.

85 The operation of this device is as follows: The screen-frame A, used as a scoop, is filled with the coal or ashes to be sifted and placed over the opening H within the rim I, by which it is held in place. The cover F, with its flanges J, is then let down on the open end and top of the screen-frame, thus closing it tightly at all points except the bottom. The sliding plate and screen thus combined are then placed over the opening K' in the ash-box and the said screen and plate reciprocated by means of handle C aforementioned, the hopper H', which projects down into said box, acting as a guide in the reciprocation. The coal and ashes are thus violently shaken 100 up within the screen-frame and the finer and worthless material precipitated between the wires D in the screen-bottom through the funnel or hopper H' and into the ash-box.

The cover F is then lifted sufficiently to allow the screen-frame loaded with the coal which has not been able to pass through it to be removed and is then let drop immediately to cover the opening H and prevent the cloud of ashes from rising up out of the box.

Having thus fully described my invention, what I claim as new, and desire to secure by Letters Patent, is—

- 10 1. In a coal-screening device, the combination of a receptacle having an opening in its top, a plate adapted to cover said opening and be reciprocated thereon, and provided with a central opening H, a frame having a screen-bottom and adapted to contain the material to be sifted and to fit over said opening H, and a cover hinged to said plate and adapted to cover said frame when in position, substantially as set forth.
- 20 2. In a coal-screening device, the combination of a receptacle having an opening in its top, a plate adapted to cover said opening and be reciprocated thereon and provided with a central opening H, a funnel-shaped hopper attached to said plate beneath said opening and tapering downward and inward, a frame having a screen-bottom and adapted to contain the material to be sifted and to fit over said opening H, and a cover hinged to
- 25 said plate and adapted to cover said frame when in position, substantially as set forth.
- 30 3. In a coal-screening device, the combination of a receptacle having an opening in its top, a plate adapted to cover said opening and be reciprocated thereon and provided with a central opening H, a frame having a screen-bottom and open at its front end and top, adapted to contain the material to be sifted and to fit over said opening H, and a cover hinged to said plate consisting of two parts hinged together and adapted to cover respectively the open end and top of said frame when in position, substantially as set forth.
- 35 4. In a coal-screening device the combination of a receptacle having an opening in its top, a plate adapted to cover said opening and be reciprocated thereon and provided with a central opening H, a raised rim sur-

rounding said opening and leaving a ledge h 50 between itself and the edges of said opening, and a frame containing the material to be sifted, having a screen-bottom and adapted to rest on said ledge over said opening H and to fit closely within said rim so as to provide 55 a rigid and secure means of connection between said sliding plate and frame, substantially as set forth.

5. In a coal-screening device a receptacle open at the top in combination with a sliding plate having a central opening H and adapted to reciprocate on said receptacle, and a shovel or scoop provided with a handle and having a screen-bottom and adapted to fit over said opening H, and a cover hinged to said plate 65 and adapted to cover the said scoop when in position, substantially as set forth.

6. In a coal-screening device a receptacle open at the top in combination with a sliding plate having a central opening H and adapted 70 to reciprocate on said receptacle, a shovel or scoop provided with a handle and having a screen-bottom and adapted to fit over said opening H, said scoop having its sides slanting upward and backward from its lip, and 75 a cover hinged to said plate at the front end of said opening H, consisting of two parts hinged together and respectively adapted to rest on the said slanting front edges and top edges of the scoop, substantially as set forth. 80

7. In a coal-screening device a receptacle open at the top in combination with a sliding plate having a central opening H and adapted to reciprocate on said receptacle, a shovel or scoop provided with a handle and having a 85 screen-bottom and adapted to fit over said opening H, and a cover hinged to said plate at the front end of said opening H, consisting of two parts hinged together and respectively adapted to rest on the front and top 90 edges of the scoop, the said parts having downward flanges at their free edges adapted to fit around the edges of said scoop, substantially as set forth.
